[57] CLAIM

The ornamental design for a tote bag with attached pouch, substantially as shown and described.

DESCRIPTION

FIG. 1 is a perspective view of a tote bag with attached pouch showing my new design;

FIG. 2 is a rear elevational view thereof, a portion of the attached pouch being broken away and omitted for convenience of illustration;

FIG. 3 is a left side elevational view thereof; and

FIG. 4 is a bottom plan view thereof.
